UNITED STATES PATENT OFFICE.

HOWARD MASON, OF AMSTERDAM, NEW YORK.

FURNACE-GRAVE.

1,283,849.

Specification of Letters Patent.

Patented Nov. 5, 1918.

Application filed April 16, 1917. Serial No. 162,332.

To all whom it may concern:

Be it known that I, HOWARD MASON, a citizen of the United States, residing at Amsterdam, county of Montgomery, and State of New York, have invented certain new and useful Improvements in Furnace-Grates, of which the following is a specification.

Reference may be had to the accompanying drawings, and the reference characters marked thereon, which form a part of this specification. Similar characters refer to similar parts in the several figures therein.

This invention relates to improvements in furnace-grates, and in certain features relates more particularly to the type of traveling grate such as a chain-grate used in connection with mechanical stokers.

The principal object of the invention is to build up such a grate in such a manner that its parts can be readily removed and replaced.

Other objects of the invention are to provide for expansion and contraction of the parts without causing undue stress or strain upon the grate-bars, and to facilitate the removal, as a unit, of the several grate-bars with the complement of finger-blocks mounted upon the respective bar.

Other objects will appear in connection with the following description.

Figure 1 of the drawings is a view in side elevation of a grate embodying my invention with the intermediate portion broken away and the furnace walls removed.

Figs. 2 and 3 are views in perspective of finger-blocks detached, adapted to be mounted upon the outer ends of the respective grate-bars.

Figs. 4 and 5 are views in perspective of finger-blocks detached, adapted to be mounted upon the inner ends of the respective grate-bars on opposite sides of an intermediate chain.

Fig. 6 is a view in perspective of one of the intermediate finger-blocks detached.

Fig. 7 is a vertical cross-section of the grate taken on the broken line 7-7 in Fig. 1.

Fig. 8 is a view in perspective of a broken-away portion of an intermediate chain.

Fig. 9 is a top plan view of the grate as shown in Fig. 1, partly broken away.

Referring to the drawings wherein the invention is shown in preferred form I have shown in Fig. 9, three chains 1, 2 and 3, ar-

ranged side by side passing over sprocket-wheels, 4, fixed upon the respective shafts, 5, which shafts are rotatively mounted in the usual manner in bearings on the furnace walls or frame, not shown. Each of these three chains has links provided with a transverse aperture, 6.

A series of rectangular bars, 7, is arranged between the chains, 1 and 2, with the bars respectively substantially aligned with apertures, 6, in oppositely located links in the chains, 1 and 2, and a similar series of grate-bars is similarly arranged between the chains, 2 and 3.

These grate-bars, 7, are all detachably connected in the same manner with the respective chains, so that a description of one will suffice for all.

The grate-bar, 7, is provided in its opposite ends with openings, 8, adapted to telescopically receive a pin, 9 or 10, inserted through an aperture, 6, in the neighboring chain-link whereby the grate-bar is mounted at its opposite ends upon the chains between which it extends.

Mounted upon the respective grate-bars, 7, are a plurality of finger-blocks, 11, 12, 13, 14 and 15, shown detached in Figs. 2 to 6, inclusive, each provided with a rectangular opening, 16, adapted to receive the rectangular grate-bar.

The finger-blocks, 15, are arranged in a series side by side longitudinally of the intermediate portion of the grate-bar. End-blocks, 11, are similarly mounted upon the outer ends of alternate grate-bars, and end-blocks, 12, are similarly mounted upon the outer ends of the other grate-bars.

Each of the end-finger-blocks, 11, 12, has an extension, 17, adapted to overhang and rest upon the neighboring chain and thereby prevent rotative movement of the grate-bar relatively to the chain-links upon which the bar is mounted.

The end finger-blocks, 13 and 14, are mounted upon the inner ends of the respective grate-bars on opposite sides of the intermediate chain, 2, and they are formed with intermeshing teeth or fingers, 18, which overhang the chain, 2.

The pin, 9, is removably inserted in the chain-link aperture, 6, and is held therein in telescoped engagement with the neighboring end of the grate-bar by means of a cotter-pin, 19, inserted through an aperture in the outer end of the pin in engagement with

an opening, 20, in the extension, 17, of the end-block, 11.

The pin, 10, may be removably inserted in the aperture, 6, in a link of the middle chain, 2, with its opposite ends in telescoped engagement with the respective alined grate-bars on opposite sides of said chain, no cotter-pin being necessary in such case.

I have shown the sides of the several finger-blocks provided with longitudinal grooves, 21, and with grooves, 22, leading therefrom through the fuel-supporting surface of the respective blocks, whereby when the blocks are arranged side by side on the grate-bar, ventilating passages are formed between neighboring blocks.

To remove the grate-bar, the cotter-pin, 19, is withdrawn and the pin, 9, is drawn out from the opening, 8, in the grate-bar, whereupon that end of the grate-bar can be raised to bring it above the level of the chain, 1, and the other end of the grate-bar can then be withdrawn from the pin, 10, and the grate-bar with its complement of finger-blocks can be removed as a unit.

The finger-blocks can afterward be removed by sliding them longitudinally of the grate-bar; and broken blocks can thus be readily replaced with new ones.

30 Where both of the outer chains, 1 and 3, are readily accessible for removal of the grate-bars in this manner, the pins, 10, may be permanently mounted upon the respective links of the chain, 2.

35 Where one of the outer chains is inaccessibly located, or where more than three chains are employed, the pins, 10, are removably mounted upon the links of the intermediate chains to permit them to be withdrawn for the removal of successive longitudinally alined grate-bars.

As many chains may be employed as are necessary to secure the desired width of grate.

45 The extensions, 17, on the outer end-blocks on neighboring grate-bars preferably have intermeshing fingers, 23, and the extensions of said end-blocks form a practically continuous shield for protecting the outer chain from the fuel and from excessive heat.

The intermeshing fingers, 18, on the blocks, 13 and 14, serve in a like manner to protect the intermediate chain, 2.

55 The facility with which the grate-bars and finger-blocks can be removed makes it possible to keep the grate in repair at comparatively low cost.

The provision for ventilation and the fact 60 that the fuel-engaging surface is made up of small integral parts lessen the tendency to warping and twisting of the grate-bars, and confine repairs practically to the finger-blocks which are the only parts of the grate

exposed to the fuel or to the direct heat of 65 the furnace.

In the preferred form of my improved grate, the grate-bar, 7, is limited in length to the space between the chains upon which the grate-bar is supported, so that the grate-bar does not overlap the chain at either end.

The intermediate portion of the grate surface between neighboring chains is made up of finger-blocks, 15, shown in Fig. 6, 75 each of said blocks having two fingers only projecting from opposite sides of the block. Each of these fingers is adapted to mesh with or extend in between under adjacent fingers on the similar blocks of the next 80 grate-bar.

What I claim as new and desire to secure by Letters Patent is—

1. In a chain-grate and in combination, 85 a chain; grate-bars in substantial alinement end to end on opposite sides of said chain severally supported at one end thereby; and finger-blocks on the respective grate-bars, certain of the finger-blocks on one side of said chain having fingers extending longitudinally of the bar intermeshing with fingers extending longitudinally of the bar on certain of said finger-blocks on the other side of said chain to form a fire-shield for the chain. 95

2. In a grate, the combination with a grate-bar; of a plurality of finger-blocks mounted side by side longitudinally upon said grate-bar, said blocks being provided with longitudinal side-grooves and with 100 side-grooves opening therefrom through the fuel-supporting surface of the blocks forming ventilating spaces between neighboring finger blocks, said finger-blocks inclosing said longitudinal side grooves. 105

3. In a chain-grate and in combination, 110 a pair of chains arranged side by side, one having a link provided with an aperture therethrough; a grate-bar extending between said chains; a pin inserted through said aperture in said chain-link in telescopic engagement with one end of said grate-bar, said pin being insertible and removable from the side of said link remote from said bar; means for detachably securing said pin 115 in telescoped engagement with the grate-bar; and means for detachably connecting the other end of said grate-bar with the other of said chains.

4. In a chain-grate and in combination, 120 a pair of chains arranged side by side, one having a link provided with an aperture therethrough; a grate-bar extending between said chains; a pin detachably inserted through said aperture in said link having one of its ends in telescopic engagement with one end of said grate-bar, said pin being insertible and removable from the side 125

of said link remote from said bar; a block on said grate-bar overhanging the other end of said pin and the chain carrying said pin, said block being provided in its overhanging end with an opening; and a cotter-pin inserted through said other end of said pin engageable with said opening in the overhanging end of said block.

5. In a chain-grate and in combination, three chains arranged side by side, the middle chain having a link provided with an aperture therethrough; a pair of longitudinally aligned grate-bars extending between the middle chain and the respective outer chains in line with said aperture; a pin removably inserted in said aperture with its opposite ends in telescopic engagement with the neighboring ends of said respective grate-bars; and means for detachably connecting the other ends of said grate-bars with the respective outer chains.

10

6. In a chain-grate and in combination, a pair of chains arranged side by side; an angular grate-bar extending between said chains; a plurality of blocks provided with rectangular transverse openings adapted to receive said angular grate-bar longitudinally of which said blocks are arranged side

15

by side, the outermost of said blocks having an extension adapted to overhang and rest 30 upon the neighboring chain; and means for detachably connecting said grate-bar with the respective chains.

7. In a chain-grate and in combination, a pair of chains arranged side by side, one 35 having a link provided with an aperture therethrough; an angular grate-bar extending between said chains; a pin removably inserted through said aperture in said link in telescopic engagement with one end of 40 said grate-bar, said pin being insertible and removable from the side of said link remote from said bar; detachable means for holding said pin in telescoped engagement with said grate-bar; means for detachably 45 connecting the other end of said grate-bar with the other of said chains; and a plurality of blocks provided with angular transverse openings adapted to receive said grate-bar longitudinally of which said blocks are arranged side by side, the outermost of said blocks having an extension adapted to overhang and rest upon the neighboring chain.

In testimony whereof, I have hereunto set my hand this 11th day of April, 1917.

HOWARD MASON.
